Frank A. Cutler,
ATTORNEY.*

UNITED STATES PATENT OFFICE.

PETER W. BLAIR, OF QUINCY, MASSACHUSETTS, ASSIGNOR TO THE HAYDENVILLE COMPANY, OF HAYDENVILLE, MASSACHUSETTS, A CORPORATION OF NEW JERSEY.

DRINKING-FOUNTAIN.

1,339,159.

Specification of Letters Patent.

Patented May 4, 1920.

Application filed January 7, 1918. Serial No. 210,626.

To all whom it may concern:

Be it known that I, PETER W. BLAIR, a citizen of the United States, residing at Quincy, in the county of Norfolk and State 5 of Massachusetts, have invented a new and useful Drinking-Fountain, of which the following is a specification.

My invention relates to improvements in drinking fountains of the type known as 10 sanitary, and more especially to nozzles for such fountains, and consists of a certain peculiar nozzle attachable within the bowl of a fountain of the said type, together with such connections and other parts and members as may be necessary or desirable in order to render the device complete, serviceable, and efficient, all as hereinafter set forth.

The primary object of my invention is to 20 provide, for a sanitary drinking fountain, a nozzle which throws a stream of water at an angle to the perpendicular, or projects such stream laterally away from the discharge orifice, outlet, or mouth of said nozzle, instead of straight upward, to the end 25 that the normal drinking point is remote from the vertical plane of said outlet, and no water that has touched the lips of a person drinking can come into contact with 30 said outlet.

A further object is to provide a nozzle, such as I have just outlined, which can be readily attached to or connected with a drinking-fountain bowl that has the customary 35 central supply opening.

Still another object is to furnish simple and convenient means for connecting such a nozzle with a bowl which is provided with a nipple in the center of the bottom thereof.

40 This nozzle and the elements of the fountain with which it is most intimately connected and associated are designed to be connected with suitable supply and waste pipes or equivalent members, with which 45 pipes or members are employed the customary pressure regulating and valve-controlling means.

The fountain equipped with this nozzle is highly efficient as well as being entirely sanitary.

50 Other objects and advantages will appear in the course of the following description.

I attain the objects and secure the advantages of my invention by the means illus-

trated in the accompanying drawings, in 55 which—

Figure 1 is a top plan of a sanitary drinking fountain which embodies a practical form of my invention; Fig. 2, a central, vertical section through said fountain, taken 60 on lines 2—2, looking in the direction of the associated arrow, in Fig. 1, and, Fig. 3, a side elevation of the nozzle detached from the other elements.

Similar numerals refer to similar parts 65 throughout the several views.

In the drawings a drinking-fountain bowl is represented at 1, which bowl is equipped with a nozzle 3, said nozzle having one end 70 located in the axial center of said bowl and the other end at one side of or beyond said center. The nozzle 3 has an outlet or mouth 4 in the outer end and opening through said end at the top thereof, the axial center of which mouth is oblique to the axial center 75 of the bowl 1.

The nozzle 3 as shown is an approximately horizontal, hollow member having the oblique mouth 4 at or in the outer terminal and an opening 5 in the bottom at 80 the other terminal. Said nozzle is provided with a sleeve 6 which has an exteriorly screw-threaded part 7 tapped into the opening 5. The sleeve 6 is interiorly screw-threaded and adapted to fit and engage a 85 nipple 8 that rises from the center of the bowl 1, and said sleeve has a dome 9 that extends into the chamber 10 within the nozzle 3. The walls of the dome 9 are perforated at 11.

90 The bowl 1 is designed and adapted to be mounted on a supply and waste casing (not shown), which casing or the supply pipe or equivalent member is provided with the necessary or desirable elements of regulation 95 and control, of usual and well-known construction and operation. An annular flange 12, on the underside of what may be termed the base 13 of the bowl 1, is provided to fit around the top of the aforesaid casing, upon 100 which latter said base is adapted to rest, and a central, vertical, screw-threaded, inlet opening 14, in said base, is provided for the upper terminal of the aforesaid supply pipe or equivalent member, which opening or 105 passage continues up through the nipple 8. The passage or inlet 14 and the continuation of such passage through the nipple 8 and

the sleeve 6 and into the dome 9 have a common axis which is in the center of the bowl 1. A waste passage 15, in the base 13, opens at the top through the bottom of the bowl, 5 and at the lower end into the space within the flange 12.

It will now be seen that the supply of water to the fountain enters the passage 14, flowing in the direction indicated by the 10 adjacent arrow, in Fig. 2, and passes through the base 13, nipple 8, and the upper part of the sleeve 6 into the dome 9, out through the opening 11 in said dome into the chamber 10 in the nozzle 3, and 15 through said chamber and the mouth 4 of said nozzle. It will be seen, further, that, owing to the location and inclination of the mouth 4, the stream of water, upon leaving said mouth, must continue upwardly 20 and toward the axis of the bowl 1 and beyond such axis until drawn by gravity into said bowl, the pressure of the water being regulated, by the means to which reference has been made, to insure the deflection 25 of said stream to the necessary extent before the water is projected over the edge of the bowl. The oblique direction of the stream of water immediately upon leaving the mouth 4 is indicated by the associated 30 arrow, in Fig. 2. The point at which the mouth is applied to the stream for the purpose of obtaining a drink is at such a distance from the mouth 4 that no portion of said stream with which the lips of the 35 person drinking come in contact does or can return to the orifice whence the stream comes.

In practice the stream rises obliquely from the mouth 4 and is projected to a 40 point approximately over the inner, closed end portion of the nozzle 3, which portion is in the center of the bowl, at or a little beyond which point preferably the mouth of the person desiring to drink is applied. 45 After passing the aforesaid point the stream falls into the bowl at some distance from the outlet of the nozzle or the mouth 4. The water in the bowl escapes through the passage 15. The velocity or force of the 50 water at and adjacent to the mouth 4 prevents a person from attempting successfully to drink at that point, and compels such person to take the drink from the stream at a sufficient distance from the said 55 mouth to obviate all possibility of contaminating the same. In order to drink to the best advantage the person should interpose the mouth in the path of the stream at approximately the point where said stream 60 begins to change from an upward to a downward course.

It is now clear that germs from the mouth 65 of a person can be deposited on the water-outlet portion of the nozzle 3 neither by direct application of the lips to such por-

tion of said nozzle, or indirectly by the falling back on said nozzle or said portion thereof of the water after contact with said mouth or lips. This fountain is, therefore, entirely sanitary in the particulars herein 70 pointed out, as hereinbefore stated.

The perforated dome 9 protects the interior supply members from foreign substances or matter that might, by accident or design, find the way or be introduced 75 into the nozzle 3, which could occur only while the water was shut off below the passage 14; and said dome also serves as a check on the water or a means to control the flow of the same, in addition to such 80 other means as may be provided for that special purpose.

The nozzle 3 can be unscrewed from the sleeve 6 and the latter from the nipple 8 in the event it becomes necessary to clear 85 or clean out the parts. In this connection attention is called to the facility with which the nozzle of the old type, which has its axis in common with the axis of the bowl, can be replaced with the new nozzle, it being necessary 90 merely to unscrew the old part or parts, accordingly as only the nozzle proper or both said nozzle and the sleeve must be changed, and screw on the new part or parts. This is an important and valuable feature. 95

More or less change in the shape, size, construction, or arrangement of some or all of the parts of this fountain may be made without departure from the spirit of my invention. 100

I am aware that means in drinking fountains for projecting a stream or a plurality of streams of water horizontally or obliquely have been used before, and do not therefore, seek to claim such means broadly. 105

What I claim as my invention, and desire to secure by Letters Patent, is—

1. An improved article of manufacture, a drinking-fountain nozzle comprising a horizontal member having therein bottom 110 and top openings at opposite ends, respectively, and a longitudinal passage with the bottom of which at one end said bottom opening communicates, and with the top of which at the other end said top opening communicates, a separable inlet sleeve attached to said member and extending through said bottom opening, and having a perforated dome within said member and communicating with said passage, the major axis of said member being approximately 115 at right-angles to the axis of said sleeve, and the axis of said top opening being oblique to the axis of said sleeve. 120

2. The combination, in a drinking fountain, with a bowl having a central vertical inlet, of an approximately horizontal nozzle having an inlet in the bottom adjacent to one end, and attached at such end to said bowl over said first-named inlet, said nozzle 125

extending laterally from the axis of said first-named inlet, having in the top adjacent to the other end an outlet the axis of which is oblique to said first-named axis, also having a communicating passage between the inlet and outlet therein, and being an integral member which has therein said bottom inlet adjacent to one end, said top outlet adjacent to the other end, and said communicating passage between said inlet and outlet. 5

10

15

3. The combination, in a drinking fountain, with a bowl provided in the bottom with a central nipple, and having a vertical inlet opening through said nipple, of a re-

movable sleeve mounted on said nipple, said sleeve having a perforated dome, and an approximately horizontal nozzle mounted on and removable from said sleeve over said dome, extending laterally therefrom, and having in the outer terminal an outlet the axis of which is oblique to the axis common to said nipple and sleeve, the connection between said sleeve and nozzle being in the bottom adjacent to one end of said nozzle. 20 25
